No. 624,808.

Patented May 9, 1899.

W. H. HOWARD.
BOWLING ALLEY BALL.
(Application filed Nov. 7, 1898.)

(No Model.)

UNITED STATES PATENT OFFICE.

WILLIAM H. HOWARD, OF MALDEN, MASSACHUSETTS.

BOWLING-ALLEY BALL.

SPECIFICATION forming part of Letters Patent No. 624,808, dated May 9, 1899.

Application filed November 7, 1898. Serial No. 695,778. (No model.)

To all whom it may concern:

Be it known that I, WILLIAM H. HOWARD, a citizen of the United States, residing at Malden, in the county of Middlesex and State of Massachusetts, have invented certain Improvements in Bowling-Alley Balls, of which the following is a specification.

Bowling-alley balls were originally made perfectly solid, but to afford means for controlling the same to better advantage finger-holes have been provided, whereby the balls could be held more securely and directed more accurately. These holes disturb the balance or equilibrium of the ball to some extent owing to its being naturally lighter on the side having the holes. Furthermore, these openings destroy the continuity of the surface of the ball, rendering it liable to jump if the edges of the openings should come into contact with the alley. In rolling a ball provided with these openings the fingers and thumb are liable to be strained and the skin broken at the points where the hand comes into contact with the edges of said openings.

Furthermore, in delivering a ball having finger-holes the palm of the hand is naturally brought to the front, necessitating a quarter-turn of the forearm, which is an unnatural position, the tendency of the arm to resume its normal position as the fingers are leaving the holes being liable to change the course of the ball. To overcome all of these difficulties and to facilitate the handling and delivery of the ball is the object of my invention, which consists in a bowling-alley ball provided with an extensible handle normally inclosed within the ball and adapted to be drawn out therefrom and grasped by the hand, said handle having a retracting-spring, whereby it is instantaneously withdrawn within the ball when released to prevent it from coming into contact with the alley as the ball rolls thereover, as hereinafter more fully set forth.

In the accompanying drawings, Figure 1 is a vertical section of a bowling-alley ball constructed in accordance with my invention. Fig. 2 is a plan view of a portion of the surface of the ball. Fig. 3 is a section on the line 3 3 of Fig. 2.

In the said drawings, A represents a bowling-alley ball which is bored out axially to form a chamber b for the reception of a slid-

ing pin or spindle B, provided at its inner end with a head c, which rests normally against the bottom of the chamber b, said spindle forming an extensible handle which when drawn out can be firmly grasped by the hand in the act of delivering or rolling the ball on the alley. The outer end of the spindle B is normally flush with and forms a portion of the surface of the ball and is preferably slightly enlarged, as shown at d, Fig. 3, to fit the flaring or countersunk mouth of the opening into which it fits.

Within the outer end of the chamber b is secured a sleeve or bushing f, through which slides the spindle B, the interior diameter of the inner portion of said bushing being enlarged to form an annular space or chamber g for the reception of a portion of a spiral retracting-spring D, one end of which bears against the shoulder h of the bushing, while the opposite or inner end rests against the shoulder i of the spindle, the spring when thus arranged serving to normally retain the spindle within the ball, as shown in Fig. 1, and also permit it to be drawn out by the hand until its head c comes into contact with the inner end of the bushing f, which forms a stop to prevent the further withdrawal of the spindle or handle. In delivering the ball the handle as soon as it is released is instantly retracted by the spring D into the position shown in Fig. 1, thus avoiding any possibility of its coming into contact with the alley as the ball rolls thereover.

To enable the handle to be easily pulled out, it is preferably provided at its outer end with undercut notches k, so that it can be seized between the finger and thumb, when it can be readily drawn out against the resistance of the spring D, the strength of which is only sufficient to insure the retraction of the handle before the ball strikes the alley. The length of the chamber g in the bushing f is preferably such as to be capable of receiving the entire spring D, whereby the head c of the handle is permitted to come into unyielding contact with the inner end of the bushing when the ball is being held by the handle in the act of delivery. As the handle B and its spring D fill the chamber b, the equilibrium of the ball remains undisturbed, and as the outer end of the handle when retracted forms an unyield-

ing portion of the surface of the ball the jumping of the latter, due to the presence of an opening, is avoided. Furthermore, by dispensing with the finger-holes the strain of the 5 fingers and the liability of breaking the skin is prevented, while it no longer becomes necessary to bring the palm of the hand to the front by a quarter-turn of the forearm, and consequently when grasping the handle the arm is 10 free to swing in a natural position to deliver the ball, thus reducing the strain on the muscles to a minimum and avoiding unnecessary fatigue.

What I claim as my invention, and desire 15 to secure by Letters Patent, is—

1. A bowling-alley ball provided with an extensible handle adapted when released to be automatically retracted within the ball, substantially as described.
- 20 2. A bowling-alley ball provided with an ex-

tensible handle normally inclosed therein, and provided with a spring for retracting it when released on the delivery of the ball, substantially as described.

3. The combination with a bowling-alley ball 25 having an axial bore forming a chamber, of a pin or spindle sliding within said chamber and forming an extensible handle for the ball, a sleeve or bushing secured within the outer end of the chamber, a spring encircling the 30 spindle and acting to retract the same within the ball when released, and a stop for limiting the outward movement of the spindle, substantially as described.

Witness my hand this 4th day of November, 35
A. D. 1898.

WILLIAM H. HOWARD.

In presence of—

P. E. TESCHEMACHER,
M. B. WILSON.
